UNITED STATES PATENT OFFICE.

LEWIS DEGEN, OF OAKLAND, CALIFORNIA.

FIRE-ALARM TELEGRAPH.

1,405,673.

Specification of Letters Patent. Patented Feb. 7, 1922.

Application filed November 13, 1919. Serial No. 337,659.

To all whom it may concern:

Be it known that I, LEWIS DEGEN, a citizen of the United States, residing at Oakland, in the county of Alameda and State of California, have invented new and useful Improvements in a Fire-Alarm Telegraph, of which the following is a specification.

This invention relates to a signalling system especially adapted for sending fire alarms; and pertains particularly to a signal system having auxiliary boxes located remote from a sub-station for actuating the sub-station signal mechanism, and to means for sending a call to the central station in case of trouble in the auxiliary box circuits. If an accidental open occurs in the auxiliary box, or the box is shunted, the test current will fail. Failure of this test current is what has been designated herein as trouble.

The objects of this invention are first, to provide a signal mechanism having two character wheels, one for sending a fire alarm code and the other for sending a trouble code, in combination with a selector to place the proper code mechanism in circuit; second, to provide means for insuring the repetition of the fire alarm code; and third, to provide novel means for tripping the substation box from the auxiliary box, or for tripping the sub-station box manually and restoring the trouble circuit connections.

These objects will be more fully understood, as will also other objects and corresponding accomplishments of my invention from the following detailed description of a preferred embodiment thereof. For the purpose of this description, reference is had to the accompanying drawings, in which:

Fig. 1 is a diagrammatic view of a fire alarm box embodying my improvement; Fig. 2 is a like view of a portion of the box illustrating the selector switch with relation to the circuit; Fig. 2^a is a diagrammatic view of the selector switch in another position; and Fig. 3 is a detailed view showing the let-off.

Referring more particularly to Fig. 1, a sub-station box is shown, and the stop wheel of any ordinary signalling train is indicated by 4. On the face of the stop wheel is the stop cam 5 having stop slots 6 and 7 disposed at diametrically opposite points. Geared in the signalling train is an arbor 8 having a fire wheel 9 and a trouble wheel 10 fixed thereto. Pivoted on the frame is a

starter 11 having a pin 12 at one end adapted to be engaged by hammers on the trigger mechanism operated from the auxiliary box circuit. On the other arm of the starter is a follower 13 adapted to be disposed in the follower stop slots for holding the stop wheel. A convenient ratio of gearing between the character wheels and the stop wheel is such that one half revolution of the stop wheel will cause four revolutions of the character wheels, whereby four rounds may be telegraphed upon release of the stop wheel. Disposed below an arm of the starter is a hand lever shown in cross section and indicated by 14. This is the usual hand lever so arranged that upon pulling the latter, the starter will release the stop wheel.

The leads for the auxiliary circuit are indicated by 15 and 16. Lead 16 is connected to a binding post, from which leads conductor 17, conductor 17 being connected to one terminal of a set of electro-magnets 18 for operating the fire alarm. The other terminal of the set 18 is connected by a conductor 19 through binding posts to a conductor 20, which leads to one terminal of a set of electro-magnets 21 controlling the trouble signal. The other terminal of set 21 is connected by a conductor 22 to a binding post, and thereby to lead 15 of the auxiliary circuit. In practice the four binding posts are connected to an auxiliary circuit having more than two wires leading to the box. However, for the sake of clearness, the connections are here shown in simplified form. This auxiliary circuit may include a source of electrical energy, such as battery 86, a resistance 87, and a pull switch 88 to short circuit the resistance. A pivoted armature 23 is disposed to be actuated by the control electro-magnet 18, and is normally held out of contact with the magnet poles by a tension spring 24. A pivoted armature 25 is disposed to be actuated by control magnet 21, and is normally held against the poles of the latter by the test current flowing in the auxiliary circuit. Disposed on one end of the armature 25 is a pin 26 located so that it will engage one arm of the lever 27, when the armature drops away from the poles of control magnet 21 due to failure of the current in the auxiliary circuit. A link 28 is secured to the other end of the lever 27 and to one end of a lever 29. Lever 29 is arranged to be engaged in the notch of a trigger 30 which is

pivoted upon the frame of the mechanism. A catch 31 of bell crank form has one arm disposed to be engaged by trigger 30 and the other arm formed with a hook adapted to be engaged by a pin 32 on hammer wheel 33. Wheel 33 has a hammer 34 arranged to engage pin 12 on the starter during its rotation. A spring 35 tends to rotate wheel 33 so that hammer 34 will engage the pin 10 on the starter and release the stop wheel.

In Fig. 1, the auxiliary fire alarm system mechanism is shown in set position ready for operation. The auxiliary circuit is of the type in which there is a test current continually flowing of sufficient strength to maintain armature 25 in contact with the poles of control magnet 21, but not sufficient to pull armature 23 against the poles of control magnet 18. Suppose that the test 20 current fails, then the armature 25 will drop, kicking lever 27. This conveys motion through the link 28 to lever 29, releasing the trigger 30. Catch 31 is then free to move so as to release the hammer wheel 33, and 25 the hammer 34 engages pin 12 on the starter releasing the stop wheel and starting the signalling mechanism. Of course, when there is an accidental opening in the auxiliary box circuit, the sub-station box cannot be 30 operated from the auxiliary box.

A pivoted trigger 36 has a foot disposed to be engaged by armature 23 when in its upper position. The upper end may be disposed to hold a catch 37 in position, so that 35 a hook on the end thereof will engage a pin 38 on a hammer wheel 39. Wheel 39 is provided with a hammer for pin 12 similar to that on wheel 33. A spring 40 tends to rotate wheel 39 so that its hammer will engage 40 pin 12 and trip the starter. A connecting link 41 secures hammer wheel 39 to a wheel 42, the latter being journaled upon the frame of the mechanism, so that upon rotation of wheel 39, wheel 42 will be 45 correspondingly rotated. On the wheel 42 is a pin 43 disposed in the slot 44 of a link 45. Link 45 is pivotally supported by a pin 46 disposed in a slot in the link. The other end of link 45 has an irregular slot 50 47 therein. A selector switch cylinder 48 is journaled on the frame and has a pin 49 riding in slot 47. Secured to a pin 50 on the cylinder 48 is a connecting rod 51, which is secured at the other end to the hand lever 55 14 by a lost motion connection, so that the link may be raised by rotation of the selector switch cylinder without disturbing the hand lever, and the hand lever may be pulled to raise the link.

60 Upon rotation of hammer wheel 39, wheel 42 is rotated by motion being transmitted through link 41. Pin 43 rides to the end of slot 44 and then moves link 45 longitudinally. Link 45 pulls upon pin 49, the latter 65 engaging the vertical part of slot 47. This

causes cylinder 48 to be rotated, and the selector switch places the trouble make and break out of operation, and the fire make and break in operation, as later described.

A spring 52 secured to cylinder 48 tends 70 to rotate the latter back into normal position. In order to prevent return of the cylinder until completion of the fire call, a pin 53 having a bevelled end is disposed thereon. A stop pin 54 secured to the frame prevents the cylinder 48 from being moved by spring 52 beyond the normal position for sending trouble calls. Mounted on a vertical pivot secured to the frame of the mechanism is a trigger 55 with its rear arm disposed in the path of pin 53. The rear arm is pressed toward the cylinder 48 by a spring. A release link 56 has a finger 57 disposed to engage the front end of trigger 55, when in its lower position, and hold the 80 rear end of trigger 55 out of the path of pin 53. Rotation of cylinder 48 will cause the bevelled end of pin 53 to engage trigger 55 and move the latter to pass above the trigger. Upward movement of link 56 will 85 move the finger 57 away from the trigger and the latter will move into the path of the pin 53, holding the cylinder against return rotation. Upon starter 11 moving into position to again lock the stop wheel, link 56 90 is pulled downward, finger 57 engaging trigger 55 and pulling the latter out of the path of pin 53, permitting the return of cylinder 48 by spring 52 to the normal position 95 of the selector switch. Thus, on movement 100 of the selector switch by pulling either the hand lever or auxiliary fire trip, the selector switch will be moved to fire position and held therein until the starter again locks the stop wheel, when the selector switch is returned to the trouble position. When the 105 starter is released by the trouble mechanism, no movement of the selector switch occurs, so that operation of link 56 does not have any function. If the auxiliary fire trip has 110 been operated, link 45 will have been rocked so that pin 49 will have reached the lower part of slot 47 and may ride along the same, when the starter through link 56 releases the switch. Thus, the trouble connections will 115 be restored without resetting the auxiliary fire trip mechanism. Hammer wheels 33 and 39 must be reset upon each operation of the same to again place them in operative 120 position.

The leads to the central station are indicated by 60 and 61. Lead 60 is connected to a contact 62 forming one element of the trouble make and break and to a conductor 63 leading to a spring finger 64 which rests 125 upon the cylinder 48 of the selector switch. The other contact of the make and break is indicated by 65 and tends to break contact with 62. Contact 65 is connected by a conductor 66 to the middle spring finger 67 130

resting on the selector switch cylinder. Leading from spring finger 68 resting on the selector switch cylinder is a conductor 69 connecting with contact 70 of the fire 5 make and break. The other contact of the fire make and break is indicated by 71 and tends to keep the circuit open. Contacts 65 and 71 are electrically connected. A conductor 72 is connected to conductor 69 at 10 the contact 70 and leads to one terminal of a non-interfering coil 73. As this element forms no part of my invention, only the electro-magnet thereof is indicated conventionally. The other terminal of the non-interfering coil is connected by a conductor 74 15 to a binding post 75 mounted upon an insulating block. The binding post 75 has the other lead 61 of the central station circuit connected thereto. Connected to binding post 75 is a contact 76 having a finger 20 for engagement with a contact 77 mounted upon an insulating block secured to the starter 11. A flexible conductor 78 connects contact 77 and the trouble contact 62. When the starter is in position locking the stop 25 wheel, contacts 76 and 77 are engaged. This shorts the box, current passing from one conductor 60 to the contact 62, through conductor 78 to contact 77, through contact 77 30 to contact 76, to binding post 75, and to lead 61. Upon the starter being released, the circuit through contacts 76 and 77 is broken, thus, removing the short.

Referring particularly to Figs. 2 and 2^a, 35 the selector switch cylinder 48, which is of insulating material has a contact 79 of conducting material mounted thereon. The cylinder rotates from the position shown in Fig. 2 to that shown in Fig. 2^a. Contact 79 40 is of such shape that spring finger 67 is always in engagement therewith. In the position shown in Fig. 2, spring finger 68 is in engagement with contact 79, thereby connecting spring fingers 67 and 68. In the 45 position of the selector switch shown in Fig. 2^a, spring fingers 64 and 67 are electrically connected.

Referring to Fig. 2, the electrical circuits are shown in the normal position for sending 50 in a trouble call. Upon the trouble armature operating, the starter is released, but the selector switch is not effected. Assume that current passes into lead 60. It will then travel along contact 62 to contact 55 65, through conductor 66 to spring finger 67. From spring finger 67 current passes through contact 79 to spring finger 68, then through conductor 69 to conductor 72, through non-interference coil 73 to conductor 74 and through binding post 75 to conductor 61. Opening of the make and break formed by contacts 62 and 65 will 60 transmit the trouble signal to the central station. It will be noted that contacts 70 and 71 are not in circuit.

Assume that the starter has been released by the hand lever or by the fire release armature. Selector switch cylinder 48 will then be moved to the position shown in Fig. 2^a. Consider the selector switch as shown 70 in Fig. 2^a substituted for that as shown in Fig. 2. Current then passes from lead 60 to contact 62, through conductor 63 to spring finger 64, across contact 79 to spring finger 67, through conductor 66 to contact 71, 75 through contact 71 to contact 70, through conductor 69 to conductor 72, and through the non-interference coil 73. From the non-interference coil current passes by conductor 74 to binding post 75, and from the latter 80 to the central station lead 61. It will be noted that in this position contacts 62 and 65 are shorted, and signals will be sent in by the fire make and break as operated by the fire character wheel. 85

Suppose that a trouble call is being sent in over the system, and that some one pulls the hand lever 14 in order to send in a fire call. Unless some mechanism is employed to cause the fire call to repeat, it may happen that only a portion of the fire call or one or more rounds may be transmitted, due to the starter locking the stop wheel. This may occur after three or more rounds of the trouble call have been sent in, in which 90 state only a portion of the fire call will be transmitted. To insure that at least three, in this instance, fire rounds may be transmitted, I have provided a mechanism shown in detail in Fig. 3. On the cam in front 100 of each of the slots are pins 80 and 81. Pivoted on the frame is a let-off lever 82 having a notch to engage a pin 83 fixed to the starter. A spring 84 tends to hold the notched end of the let-off against pin 83. 105 When the starter is in locking position, pin 83 is disposed against the straight face 85 of the let-off. Upon the starter being released, pin 83 engages in the notch of the let-off, as shown in Fig. 3. This holds the 110 starter in released position, and the stop wheel will continue to rotate as long as the let-off is in the position shown therein. One arm of let-off 82 is disposed in the path of pins 80 and 81, when locking the starter in 115 released position. Assume that the starter has been released, the let-off will lock the starter as shown in Fig. 3. One of the pins, for illustration, 80 will kick the let-off so as to release pin 83 from the notch, 120 whereupon the starter will move so that cam follower 13 rides upon cam 5. The follower can then drop in the next slot, namely, 7.

If the trouble switch has actuated the starter to release the stop wheel, then a 125 trouble call will be in the process of being transmitted. Assume that one or more trouble rounds of the trouble call have been sent in, and then the fire trip is operated or the hand lever is pulled. Although pin 80 or 130

pin 81 has already kicked the let-off so as to release the starter, further actuation of the starter will again cause it to be locked by the let-off. The starter will then be held 5 against dropping into the next cam slot, and rotation of the stop wheel will continue until the let-off has again been kicked. In this case four or more rounds of the fire signal will be sent. It may happen that a 10 trouble signal is started, for illustration from the position shown in Fig. 1, and before pin 80 reaches the let-off to kick the latter, a fire call is sent. In this case, the fire call will immediately start, the pin 80 15 will kick the let-off to release the starter and less than four rounds of fire call will be transmitted. However, the pin 80 is so disposed that at least three rounds of fire call will be transmitted. Thus, there will 20 be three rounds of fire call transmitted regardless of the operation of the trouble signalling mechanism at the time the fire call is pulled either by the hand lever or by the auxiliary box.

25 25. What I claim is:

1. In a signalling system, the combination 30 of a signal transmitter comprising a starter to render said transmitter effective, a fire character wheel and a trouble character wheel geared so as to rotate simultaneously, a fire trip for said starter, a trouble trip for said starter, a signal circuit including a fire make and break operated by said fire wheel and a trouble make and break operated by 35 said trouble wheel, a selector switch to place either said fire make and break or said trouble make and break in circuit for telegraphing, and means connecting one of said trips and said selector switch to operate the latter to correspond with the trip operated, said means normally holding said switch in position corresponding with the other trip.

40 2. A signal transmitter as specified in claim 1 including in the combination, a stop wheel, a let-off for said starter to lock the latter in released position upon tripping the same, and means on said stop wheel to release said let-off from said starter upon rotation of said wheel.

50 3. In a signalling system, the combination 55 of a signal transmitter comprising a starter to render said transmitter effective, a fire character wheel and a trouble character wheel geared so as to rotate simultaneously, a manually operable fire trip for said starter, a trouble trip for said starter, an auxiliary fire trip for said starter, a signal circuit including a fire make and break operable by said fire wheel and a trouble make and break operable by 60 said trouble wheel, a selector switch to place either said fire make and break or said trouble make and break in circuit for telegraphing, and means connecting said trouble trip and said selector switch to operate the latter to place said trouble make

and break in circuit when the latter is operated, said means normally holding said selector switch in position to operate said fire make and break.

4. A signal transmitter as specified in 70 claim 3 including in the combination, a stop wheel, a let-off for said starter to lock the latter in released position upon tripping of the same, and means on said stop wheel to release said let-off from said starter upon 75 rotation of said wheel.

5. In a signalling system, the combination 80 of a signal transmitter comprising a starter to render said transmitter effective, a fire character wheel and a trouble character wheel geared so as to rotate simultaneously, a fire trip for said starter, a trouble trip for said starter, a signal circuit including a fire make and break operated by said fire wheel and a trouble make and break operated by 85 said trouble wheel, a selector switch to place out of circuit said fire make and break when said trouble trip is operated and to shunt said trouble make and break when said fire trip is operated, means connecting 90 said fire trip and said selector switch to operate the latter to shunt the trouble make and break, and means tending to normally hold said selector switch so as to place said fire make and break out of circuit. 95

6. In a signalling system, the combination 100 of a signal transmitter comprising a starter to render said transmitter effective, a fire character wheel and a trouble character wheel geared so as to rotate simultaneously, a manually operable fire trip for said starter, a trouble trip for said starter, an auxiliary fire trip for said starter, a signal circuit including a fire make and break operated by said fire wheel and a trouble make and break operated by 105 said trouble wheel, a selector switch to place out of circuit said fire make and break when said trouble trip is operated and to shunt said trouble make and break when said fire trip is operated, means connecting 110 said fire trip and said selector switch to operate the latter to shunt the trouble make and break, and means tending to normally hold said selector switch so as to place said fire make and break out of circuit. 115

7. A signal transmitter as specified in claim 6 including in the combination, a stop wheel, a let-off for said starter to lock the latter in released position upon tripping of 120 the same, and means on said stop wheel to release said let-off from said starter upon rotation of said wheel.

8. In a signalling system, the combination 125 of a signal transmitter comprising a starter to render said transmitter effective, a hand lever for tripping said starter and a fire alarm character wheel and a trouble alarm character wheel geared so as to rotate simultaneously; an auxiliary circuit including a 130

control electro-magnet having a no-current armature and a fire alarm armature for operating said starter; trigger means for operating said starter actuated by said fire alarm armature, and trigger means for operating said starter actuated by said no-current armature; a main circuit having a make and break operated by said fire character wheel, and a make and break operated by said 5 trouble character wheel; and a selector switch for making effective for telegraphing either make and break, means tending to hold said switch in position to make effective said trouble make and break, and means 10 operated by said hand lever and said fire alarm trip to actuate said switch to make effective said fire alarm make and break.

9. In a signalling system, the combination of a signal transmitter comprising a starter 15 to render said transmitter effective, a hand lever for tripping said starter, a fire alarm character wheel and a trouble alarm character wheel geared so as to rotate simultane-

ously; an auxiliary circuit including a control electro-magnet having a no-current-armature and a fire alarm armature for operating said starter; trigger means for operating said starter actuated by said fire alarm armature, trigger means for operating said starter actuated by said no-current armature; a main circuit having a fire alarm make and break operated by said fire character wheel, and a trouble make and break operated by said trouble character wheel; and a selector switch for placing said fire make and break 20 out of circuit or shunting said trouble make and break, means operated by said hand lever and said fire alarm armature to actuate said switch to shunt the trouble make and break, and means tending to hold said selector switch so as to place said fire make and break out of circuit.

In witness that I claim the foregoing I have hereunto subscribed my name this 4th day of November, 1919.

LEWIS DEGEN.
